(57) **CLAIM**

The ornamental design for a dispensing closure, as shown and described.

DESCRIPTION

FIG. 1 is an isometric view, taken from the front, of a dispensing closure, and the closure is adapted to be mounted on a bottle or other container (not illustrated) for initial purchase by a consumer;

FIG. 2 is an isometric view taken from the rear thereof;

FIG. 3 is an isometric view taken from the front and right side thereof;

FIG. 4 is an isometric view taken from the rear and left side thereof;

FIG. 5 is a front elevational view thereof;

FIG. 6 is a rear elevational view thereof;

FIG. 7 is a left side elevational view thereof, the right side elevational view thereof being a mirror image; and,

FIG. 8 is a top plan view thereof.

The broken lines in the drawings depict environmental subject matter only and form no part of the claimed design.
